US0D1084627S

(12) United States Design Patent (10) Patent No.: US D1,084,627 S
(45) Date of Patent: * Jul. 22, 2025

(54) OUTSOLE

(71) Applicant: Zappos IP LLC, Las Vegas, NV (US)

(72) Inventors: Susan Ann Proudman, Lake Oswego, OR (US); Jeffrey Alan Henderson, Manhattan, NY (US)

(73) Assignee: Amazon Technologies, Inc., Seattle, WA (US)

() Term: 15 Years

(21) Appl. No.: 29/971,900

(22) Filed: Nov. 6, 2024

Related U.S. Application Data

(63) Continuation of application No. 29/867,661, filed on Nov. 2, 2022, now Pat. No. Des. 1,054,659.

(57) CLAIM

The ornamental design for an outsole, as shown and described.

DESCRIPTION

FIG. 1 is a front, bottom perspective view of an outsole, showing our new design;

FIG. 2 is a back, bottom perspective view thereof;

FIG. 3 is a bottom view thereof; and,

FIG. 4 is a front view thereof.

The dashed broken lines depict portions of the outsole that form no part of the claimed design.

The claimed design includes a second embodiment which is a mirror image of FIGS. 1-4.

1 Claim, 4 Drawing Sheets
